UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,739, dated September 27, 1887

Application filed July 6, 1887. Serial No. 243,556. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

The main feature of my design is the figure

A, which, in somewhat varying form and size, is substantially repeated over the face of the carpet. It consists of a central mass of vine and leaf work, from the sides of which project 20 lichen-like sprays, with occasional leaves, as is clearly shown in the photograph.

What I claim as new, and desire to secure by Letters Patent, is—

The design for carpets, consisting of the figure 25 A and the other figures, substantially as shown.

JAS. L. FOLSOM.
